COMBINED TELEVISION CABINET AND CLOCK

Charles F. Holden, Charlotte, N.C.

Application February 26, 1959, Serial No. 54,760

Term of patent 14 years

(Cl. D56—4)

Figure 1 is a perspective view of a combined television cabinet and clock embodying my new design; and

Figure 2 is a side elevational view of the clock shown in Figure 1.

The dominant features of my design reside in those portions shown in full solid lines.

I claim:

The ornamental design for a combined television cabinet and clock, substantially as shown and described.
